BUTTON BLANK FEEDING APPARATUS

Warren E. Knott, Newark, N. J., assignor to Ex-
celsior Pearl Works, Inc., New York, N. Y., a cor-
poration of New York

Application October 11, 1938, Serial No. 234,369

9 Claims. (Cl. 79—17)

This invention relates to button manufacture, and, more particularly, aims to provide a novel and valuable means for automatically delivering button blanks one by one to a succession of moving holders for the blanks, which holders form parts of a machine for operating on the blanks, as a machine operable to face or drill the blanks.

In a well-known such machine, that disclosed in U. S. patent to Barry No. 766,014, dated July 26, 1904, and known among button manufacturers, and hereinafter referred to, as the Barry machine, the blank holders are present as a plurality of upstanding columnar units, known as spindles, 10 guided and driven for bodily movement at a constant rate of speed along an endless path; said path having two straight stretches, intervening with two arcuately curved stretches lying along the fields of operation of the facing and drilling instrumentalities. The spindles, each carrying at its top a depressed horizontal seat for a blank, such seat of a diameter nearly matching that of the blank, travel continuously at a uniform speed past a blank feeding station 15 located intermediate the length of one of said straight stretches. A greater or less number of spindles pass the feeding station, per minute, depending on the speed at which the machine is run. An attendant is seated at said station, facing a tray having the button blanks therein, and it is the task of this attendant, by periodically picking up a plurality of the blanks, several at a time or one by one, and by manipulating them 20 with her finger tips, to endeavor to keep pace with the successively passing spindles by properly placing a blank in each seat. The rate of speed usually adopted for running the machine, although it could be run faster, is such that about 72 spindles pass the attendant per minute, this to face or drill approximately 30 gross of 25 blanks per hour. The usual attendant, however, is able only to feed a blank to every other spindle as it passes her, or to only two out of each three; so that the average maximum production per machine is down around 160 or 170 gross, instead of 240 gross, per 8-hour day. Furthermore, the attendant must work very rapidly, while physically and nervously tensed rather than relaxed, and with the finger tips near their most sensitive nerves constantly punished from the wear and tear of manipulating the blanks to fit them rapidly one after another in their seats.

For a great many years, these difficulties in operating the Barry machine have been a serious handicap to the art, and subject to various

attempts to overcome them. It has been proposed, for instance, in U. S. patent to me No. 817,122, dated April 3, 1906, to provide a rotary carrier for a plurality of the blanks so constructed and operating that the blanks can be 5 manually supplied thereto at a speed exceeding that at which they will be required to be supplied one by one to a means for delivering them one by one to the spindle seats; but the problem has not been solved, before the present invention, of 10 providing a satisfactory such delivery means entirely mechanical in character, simple and rugged in construction, and entirely reliable in operation.

A previously proposed unsatisfactory such delivery means, as proposed in the U. S. patent to me aforesaid, included a blank-receptor in the shape of a table overlying a line of travel of the spindles, and an ejector operated by movement of the spindle to slide the blank flat along the 15 table. The aim was by thus handling the blank to cause a movement of the blank so accompanying that of the spindle that the blank could be depended on to drop flat into the spindle seat, solely by gravity, incidental to passage of the 20 latter beyond the discharge edge of the table. The defects which resulted in the abandonment of this proposal arose in part from the fact that the ejector was given its blank-advancing movement as an accompaniment of the rocking, by an 25 advancing spindle, of a finger pivoted on an axis relative to which the spindle moved during the blank advance. The coaction between the spindle and finger was such that with the spindle moving at a constant rate of speed, the accompanying swinging of the finger caused the ejector to move at a continuously varying speed; so that it was impossible to slide the blank off the 30 table in such way as to insure that the blank would drop, solely by gravity, and surely squarely 35 into the seat, no matter at what instant any blank happened, by its own weight, and the extent of its projection beyond the table, to tilt 40 for fall from the table.

By the present invention, the ejector is given 45 its blank-advancing movement by the spindle to the seat of which such blank is to be delivered, and by the action of said spindle against a pivoted finger, but in combination with means which control the movements of the finger and actuator in such manner that the blank, during all 50 the period from the instant when it first begins to be projected off the table until the tail end of the blank completely clears the table, is moved at the same speed as the spindle, and along a 55

straight-line path of travel, and with the center of the blank held precisely vertically over the center of the spindle seat. With the parts controlled in this way, a blank is surely delivered to each and every spindle seat, with absolute certainty that it fully enters said seat to fall flat therein.

Other features of the invention have to do with an improved means for guiding a blank from the carrier for supply to the table; for guiding the blank during such supply to insure its placement in proper relation to the ejector; for positively limiting the blank to a definite path of travel during a blank-feeding movement of the ejector; for automatically modifying the means last-named to avoid jamming of the mechanism should an over-size blank be accidentally supplied; and for allowing quick and easy changes to the mechanism to adapt it for handling blanks of one size or another.

The invention will be more clearly understood, and all the various features thereof made plain, from the following description, when taken in connection with the accompanying drawings which show, by way of example, an embodiment of the invention as now favored for use with a machine of the Barry type, and wherein the manually fed carrier is a rotatable disk.

In said drawings:

Fig. 1 is a view mainly in top plan showing said embodiment operatively associated with said machine, but with only enough parts of the latter illustrated as is necessary to a full understanding of the invention.

Fig. 2 is a vertical section, taken substantially on the line 2—2 of Fig. 1.

Fig. 3 is a view similar to Fig. 1, showing on an enlarged scale certain of the parts of Fig. 1, with various overlying parts considerably broken away.

Fig. 4 is a vertical section, taken substantially on the line 4—4 of Fig. 3.

Fig. 5 is a detail view, looking in the direction of the arrow 5 of Fig. 3.

Fig. 6 is a vertical section, taken substantially on the line 6—6 of Fig. 5.

Fig. 7 is a horizontal section, taken substantially on the line 7—7 of Fig. 6.

Referring first to the parts of the Barry machine shown, the spindles are marked S, and the numeral 10 denotes a straight stretch, passing across the front of the machine, in the path of travel of an endless spindle conveyor. This conveyor is made up of spindle-carrying upper and lower sleeves 11 and 12; the upper sleeves 11 being interlinked by means of pairs of lugs 13 carried by these sleeves and which pivotally mount bell-crank 14 coupled by bolts 14', and the lower sleeves being similarly interlinked. The spindles are vertically movable in these sleeves, so as to be suitably varied in elevation on reaching different points in their path of travel, as by raising them to bring the button blanks on their tops into the fields of operation of various instrumentalities not shown for working on such blanks at locations away from the stretch 10. A part of the means for varying the elevation of the spindle tops is illustrated, the same being a cam-rail 15 over which the bottoms of the spindles slide during movement of the spindles along the stretch 10—this rail having a descending incline 15a (Fig. 2) for permitting the spindles, by their own weight, to lower themselves as they come into the stretch 10.

The endless path of travel for the spindle con-

veyor includes, at opposite ends of said stretch 10, semi-circular stretches established by the conveyor proceeding around a pair of like wheels 16 on vertical shafts 17 in such manner that the shaped outer ends 18 of arms 19 radially offset 5 from the wheels successively embrace the upper and lower spindle-carrying sleeves 11 and 12.

Through suitable driving means not shown, these wheels are always in rotation in a direction to insure continuous movement of a line of spindles S along the stretch 10 in the direction of the arrow 20.

Each spindle S has an upper mushroom-like enlargement 21, centrally above which is an up-standing adjustable chuck 22 establishing a seat 23 into which a blank is to be laid flat during travel of the spindles along the stretch 10. A clearer understanding of the showing of the drawings will be had if, as to these usual parts of a spindle S, Figs. 1 and 4 are compared.

To conclude this preliminary brief description of the ordinary Barry machine, a steadyng means for holding the spindles in line during their travel along the stretch 10 is provided in part by a guide rail 24, bearing against the lower sleeves 12 around substantially all the spindles in said stretch, and by a shorter guide rail oppositely bearing against the upper sleeves 11 around a plurality of the spindles near the center of such stretch. This shorter guide rail is provided by the front face of a shelf 25 secured to the top of a standard 26 (Fig. 4) suitably fixed in place in the machine.

Now referring to the button blank feeding means of the present invention, as exemplified in the embodiment thereof illustrated, the same as shown includes a rotatable disk 28 having a series of uniformly spaced apertures 29 therethrough arranged in a circle concentric with the axis of rotation of the disk. Almost all of these apertures, or cups, as they will from now on be called, are always closed at their bottoms during rotation of the disk, due to the fact that an underlying ring-form fixed structure 30 has a plane horizontal top surface 30a, in the form of a substantially closed annulus, always below all but a few of the cups. The structure 30 is supported, by means of a pair of oppositely offset brackets 31 and 32, on uprights 33 attached to the main frame F; these brackets including clamping-blocks 31a and 32a for anchoring the structure 30 at the desired height above the level of travel of the spindle seats as the spindles move along the stretch 10.

At its front the structure 30 carries a tray 34 for holding a large supply of button blanks 35 to be manually inserted in the cups 29, by an attendant seated in front of the tray, during rotation of the disk 28 in the direction indicated by the arrow thereon.

On top of and secured to the disk is a cap-plate 36 having an upstanding hub 36a secured by a set-screw 36' to a shaft 37 journaled in bearings 38 and 39; said shaft having a removable cap-member 37a secured thereon by a screw 65 as shown. The bearing 38 forms part of a spider portion formed in the structure 30 and one of the leg members of which is shown in part at 40 in Fig. 3. The bearing 39 is carried by a bracket 41 bolted to the structure 30 as indicated at 41a 70 in Fig. 2. Fast on the shaft 37 is a spur gear 42, meshing with a pinion 43 fixed on a shaft 43a journaled in the structure 30 (Figs. 2 and 3) and in a bearing 44 (Fig. 2) carried by the bracket 41. Also fast on the shaft 43a is a sprocket-wheel 45, 75

so placed relative to the stretch 10 that as the spindles move continuously at a uniform speed along said stretch and successively enter the successive slots of the wheel 45, each spindle rotates the wheel through 30 degrees for each advance of the spindles a distance measured by the spacing between spindles. Due to the ratio between the gear 42 and the pinion 43, the disk 28 is at the same time given a fractional rotation, in the direction of the arrow marked thereon in Fig. 2, to an extent measured by the spacing between cups 29.

By virtue of these arrangements, an attendant seated in front of the tray 34, by placing a plurality of blanks on and variously shifting them over the smooth upper surface of the relatively slowly moving disk 28, in the zone thereover within convenient manual reach, can easily keep pace with the machine when it is being operated at such speed that 72 or more spindles pass along the stretch 10 per minute, to insure that the disk is always advancing a full line of blanks, each in a cup 29 immediately ahead of which is a blank-filled such cup, toward a predetermined location above and adjacent to the stretch 10.

This location is the top of a chute 46 extended down as indicated in Fig. 3 and as shown more clearly in Fig. 4, from the upper surface 30a of the structure 30 to a table 47 placed to closely overlie a part of the path of travel of the spindle seats during travel of the spindles along the stretch 10. The structure 30 is cut away where it would otherwise extend over the table; and consequently there is an interruption of said surface 30a, in so far as it acts as a bottoming agent for the cups 29, from the upper end of the chute to just beyond a straight-line boundary 48 of such cut-out. Thus as each cup 29, carrying a blank 35, arrives over the upper end of the chute, that blank is discharged down the chute.

The chute 46 is part of a unitary element including a rectangular positioning plate 46a fitted in a recess 49 in the top of structure 30 and of the same size and shape as said plate, so that the upper surface of the plate forms a smooth flush continuation or rather a part of the surface 30a annularly on the top of the structure 30 for bottoming the cups 29 until one by one at intervals they pass beyond said plate thereupon to drop their blanks into the top of the chute.

At its side away from the front of the machine the table 47 has a dependent leaf 47a removably attached by screws 50a to a slide-carrier 50. This carrier is fixed in the position shown in Figs. 3 and 4 on the shelf 25 after being adjusted to the proper position by means including two adjusting screws 51 and 52. On the shelf is a dovetail 53, along which is horizontally slidable the bottom horizontal limb of an L-shaped bracket 54, and along the vertical limb of said bracket is a dovetail 55, along which is vertically slidable the slide-carrier 50. The adjusting screw 51, engaged adjacent its head 51a in a bearing 56 carried by the shelf 25, is at its opposite end threaded in the bracket 54 as indicated at 51' in Fig. 4. The adjusting screw 52, engaged adjacent its head 52a in a bearing 57 carried at the top of the bracket 54, is at the opposite end threaded in the slide-carrier 50 as indicated at 52' in Fig. 4.

The slide-carrier 50 is shown as a block hollowed out from top to bottom to provide a slot 58 attended by two long sides of the carrier having vertical and parallel inner surfaces, and with

the tops of said sides flat in the same horizontal plane.

The slide for this carrier, which slide is generally indicated at 59, is made up of a horizontally extending plate-like portion including a U-shaped subdivision 59a, one of the legs of which terminates in a blank-ejector in the form of a plunger 59b; the other leg of this subdivision merging into a lateral extension 59c somewhat shorter in length than the slot 58 and of a width 10 substantially as great as that of the slide-carrier 50. The table 47 is mounted on the slide-carrier so that its upper surface is flush with the top of the slide-carrier. The slide 59 all over has a flat bottom, except where such bottom is interrupted by a slide-block 60 dependent from and secured to the slide 59 by bolts 61. This slide-block, extending centrally along the bottom of the lateral extension 59c of the slide, and as long as said extension, has its parallel sides perpendicular to the flat bottom of the slide, and is of a thickness to have a nice sliding fit in the slot 58. The structure comprised by the slide 59 and the slide-block 60 rests by gravity on an extensive horizontal surface in part made up of the top of table 47 and in part made up of the top of slide-carrier 50, and so the functioning of the slide-block is merely to hold the plunger 59b to straight-line travel as revised when said plunger is to be advanced with its bottom resting 30 directly on the table.

An end portion of said slide-block 60 is seen in side elevation in full lines in Fig. 4; and the opposite end thereof then lies directly behind the line 47' marking a vertical edge of the leaf 47a 35 by which the table 47 is secured as above to the slide-carrier 50.

Stops for limiting forward and retrograde movements of the plunger 59b are provided on the slide-carrier as shown in Fig. 3, one being a 40 plate 62, and the other being a screw 63; the parts being normally held as shown by a light, quick-acting retractile spring 64 connected at one end to the slide 59 and at its other end to the slide-carrier 60. 45

The parts are always thus arranged when, following an advance of the disk 28 to discharge one of the blanks 35 by moving the cup 29 containing that blank over the top of the chute 46, said blank slides down the chute to come to rest 50 ahead of the plunger 59b as indicated at 35', in that part of a channel or guideway 66 which is flaringly enlarged toward the plunger. Such flare, in a direction away from the plunger, opens into a section of the guideway of uniform width 55 all the way to the discharge edge 47b of the table.

The table is apertured at 67, so that should a blank at any time, as by being transported with the disk 28 but not in a cup 29, drop within the 60 U-shaped subdivision 59a of the slide 59, the blank will drop through said aperture to avoid possible jamming of the mechanism.

The guideway 66 is established at one side by a member 68 which is riveted to the table 47 at 65 69. At the other side of the guideway is an assemblage of parts including a member 70 like the member 68 and likewise fixed in place on the table 47, and having pivoted thereon at 71 a plate 72 having a depending skirt 72a resting at 70 its lower edge on the top of the table and shaped vertically where it faces the guideway 66 to establish a side of said guideway which all along the length thereof is symmetrical with the side of the guideway established by the member 68, relative 75

to the line of forward travel of the center point across the nose of the plunger 59b, which line is midway between the opposite sides of the guideway section of uniform width and precisely 5 vertically above the line of travel of the center of a spindle seat below the table. The skirt 72a is spaced somewhat from the member 70, but yieldingly so, so that when a blank larger than the ones being handled accidentally is delivered into 10 the guideway 66, the forward stroke of the plunger cannot possibly jam said blank in the driveway. To this end, a threaded stud 73 is secured at one end to the skirt 72a, and passes through an opening extended transversely 15 through the member 70 as shown, which opening is enlarged at 70a to house an expansile spring 74 and horizontally widened at 70b to allow slight rocking of the stud when the plate 20 72 is rocked on its pivot 71. Yield of the plate 72 to allow emergency widening of the guideway 66 is limited by the member 70; while the stud 73 is provided with a nut and lock-nut couple, as indicated at 73a, for precise and secure setting of the parts to cause the spring 74 normally to 25 hold the skirt 72a in such position that the outer section of the guideway of uniform width will be maintained as above-described during handling of blanks of the size intended to be handled.

30 Transversely extended over a part of the guideway 66 is a roofing member 75 one end of which rests on the plate 72 and the other end of which is secured at 75' to the top of member 68; this member having a lip 75a upwardly extended therefrom toward the top of the chute 46 and so placed relative to the bottom of the chute that a blank coming down the latter so as bouncingly to strike the guideway engages the underside of said lip and is guided by the same to 35 fall flat into the space between the nose of the plunger and the flaring sides of the guideway.

At the bottom of the slide block 60 is pivotally mounted a finger 76, held by a heavy retractile spring 77 to an angular set as shown in broken 40 lines in Fig. 3 and so as to have its free end in the path of movement of a spindle during passage of the spindle below the table 47. As the parts are shown in Fig. 3, a spindle under the table has advanced just far enough to abut 45 against the finger. A lug 76a on the finger, and shown in full lines at the upper part of Fig. 3, is forced by the spring 77 against a screw 78 carried by the slide-block 60; so that by adjustment of this screw, which is threaded in an extension 50 60a shown in Fig. 4 as dependent from one end of the slide-block, said angular set of the finger 76 can be provided for exactly as desired. The spring 77 is connected at one end to the lug 76a (Fig. 3) and at its other end to the slide-block 55 extension 60a (Fig. 4). This spring is stiff enough, as compared with the relative ease of travel of the slide 59 toward the right in Fig. 3, to prevent rocking of the finger on its pivot 79; thereby to cause the latter to move with said 60 spindle, and consequently to cause the plunger 59b to perform a blank-feeding stroke, during movement of the spindle to the right in Fig. 3. This action of the spring 77 is not interfered with, until the plunger has completed its full 65 blank-feeding stroke, to an extent such that the tail end of the blank clears the table edge 47b under push from the plunger so that said blank at the instant of such clearance is moving at the same speed as the plunger.

The speed of advance of the plunger is the same as that of the spindle, because the spring 77 prevents a movement of the spindle relative to the finger-pivot 79, and hence there is relative immovability between the finger 76 and the 5 spindle. Also, the finger is so angularly set on its pivot 79 by proper adjustment of the screw 78 that at the instant the plunger starts its forward movement to begin to advance the blank with the spindle, the center of the spindle seat 10 is vertically below a horizontal line across the guideway 66 perpendicular to the line of travel of the plunger and containing the center of the blank. Furthermore, the blank, following its entrance into the outer guideway section of uniform width, is kept to a straight-line advance along a path directly overlying the similar path of advance of the spindle seat, and the blank is held to this advance until it has been projected so far off the table as to drop by its own weight 20 therefrom. In this last connection, it will be noted that the member 68 and the skirt 72a are prolonged sufficiently beyond the discharge edge 47b of the table to have these elements 68 and 25 72a act guidingly on the opposite sides of the blank even after the front end of the blank has been given a considerable degree of projection beyond said edge.

Consequently, all the while the blank and the 30 spindle seat to receive the blank are simultaneously moving toward and beyond the discharge edge 47b of the table, up until the instant the blank clears the table top to drop flat into the spindle seat, the center of the spindle seat is precisely vertically below the center of 35 the blank—so that the front end of the blank is directly vertically above the front end of the spindle seat not only when the latter starts to emerge from under the table but also all during the continuation of this emergence prior to the 40 time of drop of the blank off the table and into the seat; with the result that the blank in every instance is certainly properly received in the spindle seat.

The described action of the spring 77 is not 45 interfered with until the plunger has performed such a working stroke as will deposit the blank in the spindle seat as just described. At the end of this stroke, the slide structure carrying the plunger 59b is halted by the stop-screw 63, and 50 thereby the finger is rocked despite the spring 77 to allow passing of the spindle beyond the finger. Thereupon the spring 77 restores the finger to the position shown in Fig. 3, while the spring 64, tensioned by the just concluded forward stroke of the plunger, causes the latter to perform its retraction stroke to bring it again to the position shown in Fig. 3 and in readiness to have supplied to it the next blank on the disk 55 28. Just before the next succeeding spindle arrives under the plunger, said blank is thus supplied, its carrying cup 29 having arrived in time 60 for this over the top of the chute 46.

The spindle last-mentioned, and each following 65 spindle, when each of these spindles arrives under the table 47 below the plunger 59b, similarly co-acts with the finger 76, and in such timed relation with the movement of the disk 28 that a blank 35 is delivered to the table in front of the 70 plunger as in Fig. 3 just before each such coaction. Thus as each spindle moves along under the table 47 the blank intended for the seat of that spindle moves with the spindle in such manner that incidental to passing of said seat beyond 75

the edge 41b of the table said blank drops flat into said seat.

It should be explained that the Barry machine is so constructed that the upper portions of the 5 spindles carrying the chucks 22 within which are the spindle seats 23 are readily removable, so that chucks for receiving one size of blank can be readily replaced by chucks for handling another size of blank; and also that these chucks, 10 hereabove described as adjustable, are adjustable in the sense that by the operation of the Barry machine they are automatically opened up during approach of the spindles to the stretch 10, to facilitate the previous direct manual insertion 15 of the blanks in the seats, and they are automatically contracted after leaving the stretch 10 to hold the blanks concentric with the spindle centers while the blanks are worked on by the machine. In other words, when by the mechanism 20 of the present invention a blank is discharged from the table 41 to drop flat into a spindle seat, this seat is then of a diameter somewhat exceeding that of the blank; which is perhaps one reason why in practice the present 25 invention operates so unerringly.

The embodiment of the invention herein described can be easily and quickly adapted, after completion of a run of blanks of one size, for handling a run of blanks of another size. By 30 way of the screws 50a, the table 41 can be removed, and another table substituted therefor having elements corresponding to the elements 68 and 12a so placed on the substituted table to establish a guideway like the guideway 66 but 35 laterally dimensioned to agree with the size of blank now to be handled. To facilitate this change of tables, the disk 28 is removed; in preparation for which it is merely necessary to take out the screw holding the cap-member 37a 40 on the top of shaft 37, and loosen the set-screw 36'. By removal of the disk 28, also, the chute 46 is made quickly replaceable by another similar chute but one laterally dimensioned to agree with the new size blank.

45 While there has been illustrated and described in great detail a now preferred embodiment of the invention, the latter may be otherwise embodied as well as variations made in the illustrated embodiment, without departing from the spirit of 50 the invention, and parts of the improvements may be used without others; and so the invention is not to be limited to the constructions and arrangements herein set forth, but the scope of protection contemplated is to be taken from the 55 claims following, interpreted as broadly as is consistent with the prior art.

I claim:

1. In a mechanism for feeding button blanks to seats in the tops of a succession of vertical spindles during travel of the latter at a uniform speed along a straight-line path, the combination, with a table overlying said path and having an edge transverse to said path toward and beyond which edge said spindles travel, of a 60 slide; a plunger carried by the slide and having its head resting on said table, said head for engaging a blank lying flat on the table and thrusting said blank to and over said edge for gravity drop into a spindle seat as said seat passes 65 said edge; guiding means for holding the slide to forward and retraction straight-line strokes parallel to said path; means for halting said retraction stroke when the plunger head is in rear of said edge by a distance greater than the diameter 70 of a blank; a spring for normally holding the

slide retracted against said halting means; blank guiding means relative to which the slide is reciprocable, said blank guiding means extended over the table from near said edge to near the plunger head when the slide is in retracted position; a stop on the slide; an arm pivotally mounted on the slide and having a part engageable with said stop, said arm being shaped and pivotally mounted on the slide so that when engaged with said stop an end of the arm is positioned for 10 engagement by a spindle moving toward said edge at the instant the tail end of the spindle seat is substantially vertically below the plunger head and so that the spindle thrust against the arm is in a direction to swing it away from 15 said stop, said arm being thus swingable to clear the spindle; means for insuring that the arm and slide will move as one unit and hence the plunger will move at precisely the same speed as the spindle in response to its thrust against the 20 arm, said means including a spring connecting the arm and the slide and acting to force the arm against the stop, said spring being stronger than the spring first-mentioned to maintain the arm against the stop by virtue of yield of the 25 spring first-mentioned during a forward stroke of the slide to advance the plunger head sufficiently to thrust a blank to gravity-drop projection over said edge; and means for predeterminedly causing thrust of the spindle against said 30 arm to overcome said stronger spring and swing the arm away from said stop, the means last-mentioned including a stop positioned to engage and halt forward movement of the slide, thereby to permit movement of the spindle beyond the halted slide, and thereby in turn to free said arm from the spindle and so permit the spring first-mentioned to retract the slide, to which end this spring is strong enough to overcome the friction between the slide and its guiding means. 35

2. In a mechanism for feeding button blanks to seats in the tops of a succession of vertical spindles during travel of the latter at a uniform speed along a straight-line path, the combination of a table for supporting flat thereon a blank for deposit in a spindle seat by gravity drop over an edge of the table overlying and transverse to said path as said seat passes beyond said edge; a slide; a plunger fixed on the slide and having its head resting on the table; a guiding means for the slide to hold the plunger head to a straight-line travel in the direction of travel of the spindle; a second guiding means relative to which the plunger moves and coacting with the table for guiding said blank to straight-line travel in said direction under thrust of the plunger head toward said edge; a spindle-engaging means carried by the slide for causing the plunger head to be moved by the spindle 60 in said direction and precisely at the same speed as the spindle until the spindle seat passes beyond said edge, said means including an arm, means pivotally mounting the arm on the slide, a stop on the slide, said arm swingable toward and away from said stop, said arm when swung against said stop being extended into the path of travel of said spindle for engagement by the latter to urge said arm away from said stop at the instant when the tail end of the spindle seat is substantially vertically below the plunger head, said arm being swingable away from the stop to clear the spindle, and a spring strong enough to hold the arm against the stop despite said thrust of the spindle against said arm; and means for 65 70 75

causing a retraction stroke of the slide, said means including a spring weaker than the spring first-mentioned for returning the slide to retracted position when the arm is swung away from the stop to clear the spindle, and a second stop, fixed relative to the table, for overcoming the spring first-mentioned to allow thrust of the spindle against the arm to swing the latter to clear the spindle when the forward stroke of the slide has advanced the plunger head sufficiently to thrust the blank to gravity-drop projection over said edge.

3. In mechanism for advancing a button blank for gravity-drop delivery to a seat in the top of a vertical spindle during travel of the latter, the combination of a receiving table for a blank to support the same flat; a reciprocable plunger movable toward an edge of the table for thrust against the blank to project it beyond said edge for gravity-drop into said seat as said seat passes beyond said edge, the table so overlying the line of travel of the spindle that its seat passes under the table toward and beyond said edge; a blank guiding means including the table for maintaining the blank in line with the plunger during said thrust; yielding means for retracting the plunger and tending to hold it in retracted position; an advancing means for the plunger operated by travel of the spindle, said means including a spindle interceptor, means mounting said interceptor on the plunger and including an operative connection to permit movement of the interceptor relative to the plunger for clearing the interceptor from the spindle under thrust of the latter, and means including yielding means more resistant to yield than the yielding means first-mentioned for preventing relative movement between the interceptor and the spindle thereby to permit thrust of the spindle against the interceptor to advance the plunger at precisely the same speed as the spindle; and means fixed relative to the table for overcoming the second-named yielding means when the forward stroke of the plunger has proceeded sufficiently to thrust the blank to gravity-drop projection over said edge.

4. A mechanism as in claim 3, in which said blank guiding means includes a pair of elongate members above and spaced over the table to establish between them a guideway having oppositely facing side walls one carried by each of said members, said members being so shaped that said walls provide an outer length of uniform width for said guideway and an inner length for said guideway which gradually increases in width toward the location of the plunger in its retracted position.

5. A mechanism as in claim 3, in which said guiding means includes a pair of elongate members shaped and spaced over said table to form between them and with the table top a guideway for a blank during its travel under thrust of the plunger toward said table edge, said guideway being of uniform width over a length thereof adjacent to and at said edge and along this length thereof having a bottom wall provided by the table top as well as side walls provided by said members, said members being prolonged beyond said edge to open the bottom of said guideway between the length thereof measured by said prolongations.

6. A mechanism as in claim 3, in which said guiding means includes a pair of elongate parallel structures coacting with the table top to form a straight channel of uniform width adjacent to said table edge, one of said structures being fixed to the table, and the other including an elongate support fixed to the table, an elongate plate, means mounting said plate on the side of said support facing the other of said structures, and yielding means for normally maintaining said plate at a predetermined spacing from the structure first-mentioned to allow said plate to be forced in toward said support during movement of an over-size blank through said channel.

7. A mechanism as in claim 3, in which said blank guiding means includes a pair of elongate members above and spaced over the table to establish between them a guideway having oppositely facing side walls one carried by each of said members, said members being so shaped that said walls provide an outer length of uniform width for said guideway and an inner length for said guideway which gradually increases in width toward the location of the plunger in its retracted position, and in which there is a chute overlying said outer length and downwardly inclined in a direction opposite to that of forward travel of the plunger and having its lower end transverse to said inner length and adjacent to the joining of the latter with the outer length.

8. A mechanism as in claim 3, in which said blank guiding means includes a pair of elongate members above and spaced over the table to establish between them a guideway having oppositely facing side walls one carried by each of said members, said members being so shaped that said walls provide an outer length of uniform width for said guideway and an inner length for said guideway which gradually increases in width toward the location of the plunger in its retracted position; in which there is a chute overlying said outer length and downwardly inclined in a direction opposite to that of forward travel of the plunger and having its lower end transverse to said inner length and adjacent to the joining of the latter with the outer length; and in which there is a roofing plate over said inner length, high enough to clear said plunger, and there is a lip upwardly extended away from said plate in the direction of forward stroke of the plunger and overlying a part of the length of the chute near its lower end and high enough above the chute to clear a blank sliding down the chute.

9. A mechanism as in claim 1, in which said slide includes a substantially horizontally lying U-shaped plate-like subdivision resting on the table, one of the legs of the U forms said plunger, the interior of the U at the bowl thereof facing in the direction of forward stroke of the plunger, and there is an opening through the table between the legs of the U and spaced ahead of the bowl of the U a distance substantially equal to the length of forward stroke of the plunger when the latter is in retracted position, whereby the U provides a sweep for engaging a blank on the table out of line with the plunger and advancing said blank to said opening for discharge therethrough by forward stroke of the slide.
